UNITED STATES PATENT OFFICE.

HOWARD HARLAN, OF RICHMOND, VIRGINIA.

DEVICE FOR INTRODUCING AIR INTO STEAM-BOILER FURNACES.

^ SPECIFICATION forming part of Letters Patent No. 627,688, dated June 27, 1899.

Application filed May 2, 1899. Serial No. 715,361. (No model.)

To all whom it may concern:

Be it known that I, HOWARD HARLAN, a citizen of the United States, residing at Richmond, in the county of Henrico and State of Virginia, have invented certain new and useful Improvements in Devices for Introducing Air into Steam-Boiler Furnaces; and I do declare the following to be a full, clear, and exact description of the invention, such as will 5 enable others skilled in the art to which it appertains to make and use the same, reference being had to the accompanying drawings, and to the letters of reference marked thereon, which form a part of this specification.

This invention relates to certain new and useful improvements in devices for introducing air into steam-boiler furnaces to produce a more complete combustion of the gases in 10 the furnace, and more specifically the invention resides in the provision of a furnace having preferably a double-arch ceiling supported at its center on a fireproof column, said arch extending from the bridge-wall over portions 15 of the grate and having recesses or apertures in the bridge-wall, through which air is conveyed from the outside to the spaces above the grate and underneath the arches, suitable provision being made for regulating the supply of air 20 which enters through ducts leading from the rear wall of the furnace through into the furnace proper, said ducts being preferably below the upper or highest portion of the arch or bridge-wall for the purpose of protecting 25 the same from excessive heat.

To these ends and to such others as the invention may appertain, the same consists, further, in the novel construction, combination, and adaptation of parts, as will be hereinafter more fully described and then specifically defined in the appended claim.

My invention is clearly illustrated in the accompanying drawings, which, with the letters of reference marked thereon, form a part 40 of this application, and in which similar letters of reference indicate like parts throughout both views, in which—

Figure 1 is a vertical sectional view through the furnace on line 1 1 of Fig. 2. Fig. 2 is 45 a vertical cross-sectional view.

Reference now being had to the details of the drawings by letter, A A designate the arches over the grate-sections B, and the inner ends of said arches are supported on the fire-proof column C. These arches extend, preferably, a considerable distance over the grates, as it is found from practice that the best results are obtained by a construction of this kind, the air entering through the bridge-wall from the outside through the back or side wall. 55 In the recessed portion D of the bridge-wall D' the pipes E enter, there being preferably two under each arch, as shown, and these pipes open near the upper end of the bridge-wall. Leading from the recesses D in the 60 bridge-wall are apertures d, opening through from the said recesses into the space above the bridge-wall. The outer end of each of said flues or pipes E is provided with a slide-valve G, which works in the vertical slots in 65 the casing H, secured to the end of the flue, whereby as the said slide is raised or lowered the supply of air may be regulated. These flues E are preferably horizontally disposed 70 in the furnace and are made of any suitable material to protect them from the excessive heat which passes over the bridge-wall in its course to and through the flues of the boiler 75 above.

From the foregoing it will be noted that 80 by the construction of a double curve or dip bridge-wall I am enabled to utilize the air which is introduced for the purpose of completing the combustion to the best advantage, as has been proven by experiments in the art. 85

I am aware that it is common in the art to produce steam-boiler furnaces in which air is introduced into the furnace adjacent to grates from the outside, and I make no claim for such construction. 90

Having thus described my invention, what I claim to be new, and desire to secure by Letters Patent, is—

A device for introducing air into steam-boiler furnaces, comprising the combination 95 with the bridge-wall, recessed as at D near its upper end, the horizontal flues E communicating with said recesses at their inner ends, and their outer ends having communication with the outside atmosphere, said flues being be- 100

low the upper end of the bridge-wall, and having sliding stops at their outer ends, whereby the supply of air which it is desired to introduce into the furnace may be regulated, the double arch with apertures *d* leading into the said recesses in the bridge-wall, the central column supporting the inner ends of said arches, which latter extend over the

grates a suitable distance, as shown and described.

In testimony whereof I affix my signature in presence of two witnesses.

HOWARD IIARLAN.
